UNITED STATES PATENT OFFICE.

LEWIS M. SCHOMBER, OF SHIRLEY, INDIANA.

DISH-DRYING RACK.

No. 901,747.

Specification of Letters Patent.

Patented Oct. 20, 1908.

Application filed January 9, 1908. Serial No. 410,050.

To all whom it may concern:

Be it known that I, LEWIS M. SCHOMBER, a citizen of the United States, residing at Shirley, in the county of Hancock and State 5 of Indiana, have invented certain new and useful Improvements in Dish-Drying Racks, of which the following is a specification, reference being had therein to the accompanying drawing.

10 My invention relates to improvements in plate and saucer drying racks as hereinafter described in the specification and particularly pointed out in the claims.

15 The object of this invention is to provide a plate and saucer drying rack that will be light, durable, and simple in its construction.

In the accompanying drawings like numerals of reference designate like parts throughout the several views.

20 Figure 1 is a side elevational view of the rack; and, Fig. 2 is a top view of the same.

My plate and saucer drying rack is constructed entirely of wire and consists of a series of wires 1 arranged at equal distances 25 apart and situated in parallel relation to each other, each one of which is bent at or near its ends to form the larger upwardly extending bows 2 and the smaller upwardly extending bows 3. At the bottom ends of the legs of each 30 of said bows are formed the lower supporting loops 4, 5, 6, and 7 which form the supporting feet of the rack. The series of wires, thus formed, are connected and held rigidly in their proper positions and distances apart 35 by the tie-rods 8, 9, 10, and 11 which latter are soldered, welded, or otherwise permanently secured at their points of contact with the horizontal wires 1 and the legs of the bows 2 and 3 to maintain said wires and the 40 bows thereof in their relative positions and at their proper distances apart.

The rods 8, 9, 10, and 11 form supports for the bottom sides of the plates and saucers to support them in position between said bows 45 2 and 3.

The rack is constructed in the following manner:—I first take a straight wire 1 of suitable diameter and length and form at one end thereof the inner supporting loop 4. I 50 then bend the said wire to form the larger upright bow 2 so that the inner leg of said bow extends from the inner supporting loop 4. I then bend the wire 1 to form the outer supporting loop 5, then bend the straight por-

tion of said wire to and against the legs of the 55 loop 2 to extend over the supporting loop 4. I next form the supporting loop 6 on the opposite end of the wire 1, then bend said wire to form the smaller bow 3 so that the inner leg of said bow extends from the inner supporting loop 6. I then form the outer supporting loop 7 and finally bend or twist the wire 1 at a point situated at the top of the outer supporting loop 7 to move the legs of the bow 3 to and against the straight portion 60 of the wire 1, so that the inner supporting loop 6 will be situated under the straight inner portion of the wire 1. I proceed in this manner with each of the wires constituting the rack till the required number of wires are 65 formed. I next arrange the wires, thus formed, at their proper and equal distances apart and in parallel relation, and temporarily secure them, by any suitable means, in position. I next take the straight wires 8, 9, 70 10, and 11 and place them in their respective positions, as shown in the drawings, that is, the tie-rod 8 is situated to extend over the outer supporting loops 5 in such position 75 thereon so as to contact with the outer legs 80 of all the bows 2 and the top portions of the supporting loops 5 and said wire is secured at its points of contact with said loops and the outer legs of the bows to rigidly maintain said bows in their vertical positions and in parallel relation the one to the other.

The tie-rod 9 is situated to extend over the wires 1 above the inner supporting loops 4 so as to contact with the inner legs of the bows 2 and the wires 1, and the said tie-rod 9 is secured permanently to said legs and said 90 wires as before.

The tie-rods 10 and 11 are arranged in position relatively to the bows 3 and the supporting loops 6 and 7 and secured in like 95 manner thereto. The said tie-rods not only operate as braces for securing the several bows in their relative positions, but also serve the purpose of supports or rests upon which the plates and saucers placed in the 100 spaces between the bows 2 and 3 rest and are supported in position.

I claim:—

In a dish drying rack, the combination with a series of horizontally extending wires 105 arranged in parallel relation to each other, vertically extending bows formed integral at the ends of each of said horizontally extend-

ing wires, and integral supporting loops at the bottom of said bows, said loops being disposed beneath the horizontal wires, of straight rods extending at right angles to 5 said horizontally extending wires and rigidly fastened thereto and to each of said loops of each bow.

In testimony whereof I affix my signature in presence of two witnesses.

LEWIS M. SCHOMBER.
